UNITED STATES PATENT OFFICE.

HERBERT W. SELLNER, OF FARIBAULT, MINNESOTA.

SANDPAPERING-MACHINE.

1,094,484.

Specification of Letters Patent. Patented Apr. 28, 1914.

Application filed October 14, 1912, Serial No. 725,594. Renewed November 15, 1913. Serial No. 801,253.

To all whom it may concern:

Be it known that I, HERBERT W. SELLNER, citizen of the United States, residing at Faribault, in the county of Rice and State of Minnesota, have invented certain new and useful Improvements in Sandpapering-Machines, of which the following is a specification.

This invention relates to improvements in machines for sandpapering or polishing the surfaces of articles of wood or other materials, and particularly to the mechanism of such machines by which pressure is applied to the polishing member.

The especial objects of the improvements hereinafter described are to provide flexible means for applying the pressure on an endless polishing or sandpapering belt, and means coöperating with said flexible means whereby the pressure upon any given area may be increased or diminished with great nicety, thus simulating the results accomplished by hand polishing which is generally conceded to be superior to machine work.

In the accompanying drawing I have illustrated my invention in an approved form in the following views:

Figure 1 shows in side elevation my improvements applied to a sandpapering machine of conventional form, only so much of the machine proper being shown, as is necessary to disclose the operative connection of my improvement. Fig. 2 is an end elevation of the pressure controlling mechanism which constitutes my invention. Fig. 3 is a top plan view of my invention; and Figs. 4 and 5 are details of the pressure shoes and adjacent parts.

Referring to the details of the drawings, 6, 6, represent the end supporting standards of a polishing machine on which are mounted pulleys 7 and an endless sandpaper or polishing belt 8, a work supporting table 9 with adjusting devices 10, 10^a, all of which form no part of my invention but are merely included to show the operative connections.

6^a represents a rear frame member of the machine which is rigidly connected with standards 6, and supports the operative parts of my invention.

11, 11, represent bracket frames of corresponding form, which are arranged near the standards 6, and are connected with the frame member 6^a by parallel links 12, as clearly shown in Fig. 2. The brackets 11 are

formed with forward extensions 11^a, and rearward angular extensions 11^b.

Rods 13 have their forward ends fixed in the extensions 11^a, and their rear ends are secured in the ends of a bar 15 which extends longitudinally of the machine and is rigidly connected at its ends with the brackets 11. At the center and rear side of the bar 15, is an arm 15^a, to which is connected the inner end of a lever 14 which is pivoted at 14^a on the frame member 6^a, and has a counterweight 14^b adjustably mounted thereon, which is designed to neutralize gravity in its action on the frame made up of the brackets 11 and the members supported thereby.

16 represents a rectangular, in cross-section, pressure bar, the ends of which are loosely held in openings 11^d in the extensions 11^c of the brackets 11, and are vertically adjustable therein by screws 11^e. Upon the bar 16 are arranged a number of shoes 17, (Figs. 4 and 5) the bar 15 passing through an opening 17^a in each shoe and held under compression therein by a coil spring 17^b which bears 80 downwardly upon the bar. The upper surface of each shoe is convex as at 17^c, and the bottom or base is flat, as at 17^d. To the under side of the base 17^d, is glued, or otherwise secured, a flexible leather strip 8^a 85 which engages the sandpaper or polishing belt 8.

18 represents a pressure roller which is arranged diagonally above and in frictional contact with the convex tops of the shoes 90 17. The spindles 18^a of the roller 18 are journaled in blocks 19 slidably mounted on the rods 13. The blocks 19 are actuated by means of links 20 pivotally connected therewith and with one arm of bell-crank levers 95 21, 21. The other arms of these levers are pivotally connected with the opposite ends of a bar 22. In the center of the bar 22 is a vertical stud 23 which fits loosely a slot 24^a in a lever 24 pivoted at 24^b to the extension 100 15^a of the bar 15. The free end of the lever terminates in a handle 24^c by which it may be manually operated.

From the construction described, it appears that a movement of the lever 24 in a horizontal plane, either to the right or left, will cause the roller 18 to move over the tops 17^c of the shoes 17 and thereby depress said shoes vertically to an extent dependent upon the relative positions of the roller and the convex surface of the shoe which it engages, it being understood that the spindles

- of the roller 18 have no vertical movement, while the shoes will yield with the compression of the springs supporting them. As the sanding belt 8 passes below the strip 8^a, 5 it will be pressed downwardly by the shoes. As the bar 16 is adjustable vertically by the screws 11^a the degree of compression of the springs 17^b is controlled by raising or lowering said bar.
- 10 Having thus described my invention, what I claim as new is:—
1. In sanding or polishing machines, comprising a traveling belt and means for driving same, a swinging frame, a plurality of 15 shoes mounted under tension on said frame, a single continuous pressure member arranged above and in contact with said shoes in a plane diagonal thereto, means for moving said member over said shoes, and means for regulating the tension of said shoes.
  2. In a sanding machine, comprising a traveling belt, and means for driving same, a swinging frame, a plurality of shoes mounted under tension on said frame and 25 having convex tops, a single continuous pressure roller arranged above and in contact with said shoes in a plane diagonal thereto, means for moving said roller over said shoes, and common means for regulating the tension of said shoes.
3. In a sanding or polishing machine comprising a traveling belt and means for driving same, a swinging frame, a roller mounted on and extending longitudinally of said frame, a plurality of shoes adapted to be 35 depressed by said roller, yielding adjustable means for adjusting said shoes relative to said roller, said means common to all of said shoes, and means for adjusting said roller relative to said shoes. 40
4. In a sanding or polishing machine, comprising a traveling belt and means for driving same, a row of shoes, a flexible strip secured to the bottoms of said shoes, a bar extending longitudinally through said 45 shoes, yielding bearings between said bar and each of said shoes, means for adjusting said bar, a pressure member extending diagonally of said row of shoes and in frictional engagement therewith, and means for 50 varying the position of said member relative to said shoes substantially in the manner set forth.

In testimony whereof I affix my signature in the presence of two witnesses.

HERBERT W. SELLNER.
